UNITED STATES PATENT OFFICE.

ERNEST S. JOHNSON, OF WEBSTER CITY, IOWA, ASSIGNOR TO KNAPP-MONARCH COMPANY, OF ST. LOUIS, MISSOURI, A CORPORATION OF MISSOURI.

ELECTRIC HEATER.

Application filed February 27, 1928. Serial No. 257,254

The object of my invention is to provide an electric heater of simple, durable and comparatively inexpensive construction.

More particularly it is my object to provide an electric heater wherein the heating element is adapted to be mounted upon a pair of terminal posts whereby it may be readily removed from the terminal posts or placed thereon.

10 Still a further object is to provide a heating element including a core of non-conducting material having a pair of spaced openings therein adapted to receive the ends of a pair of terminal posts, the core having an electric 15 resistance wire mounted thereon having the ends thereof extended into the openings in said core whereby the core may be both supported on the terminal posts and at the same time, the resistance wire is contacted thereto.

20 Still a further object is to provide a heating element which is adapted to be supported on a pair of terminal posts, the terminal posts also serving as a means for transmitting electric current to the resistance wire forming a 25 part of the heating element.

With these and other objects in view my invention consists in the construction, arrangement and combination of the various parts of my device, whereby the objects contemplated are attained, as hereinafter more fully set forth, pointed out in my claims and illustrated in the accompanying drawings, in which:—

Figure 1 is a perspective view of my improved heater.

Figure 2 is a central vertical sectional view through the same.

Figure 3 is a horizontal sectional view taken on the line 3—3 of Figure 2.

40 Figure 4 is a perspective view of the heating element; and

Figure 5 is a detail sectional view taken on the line 5—5 of Figure 4.

In the accompanying drawings I have used the reference numeral 10 to indicate generally a base to which is pivotally connected a reflector bowl or shell 12. The bowl or shell 12 has mounted thereon a guard 14. The guard 14 is formed of a number of spring 45 wires adapted to extend over the periphery of the shell 12 and to be retained thereon by the resiliency of the wires themselves.

Within the shell 12 is mounted a pair of terminal posts 16 and 18. The posts 16 and 50 18 project through a pair of insulating ele-

ments or sleeves 20 which are mounted within the shell 12. The terminal posts have nuts 22 and 24 mounted on each side of the insulating sleeve 20 wherein the posts are properly positioned and held relative to the shell 12.

On the outside of the shell 12 is a small housing 26 adapted to extend around and cover the outer ends of the terminal posts 16 and 18. An electric wire 28 extends through the shell 20 and has one line connected to the binding posts 16 and its other line connected to the binding posts 18.

From the construction of the parts just described, it will be seen that the two posts 16 and 18 are included in an electric circuit. The two posts 16 and 18 project into the shell 12 for a considerable portion of their length. Upon the posts 16 and 18 I mount a heating unit A. The heating unit A includes a core 30. The core 30 is of a non-conducting or insulating material such as porcelain, lava or the like.

In the drawings I have shown the core as tubular in outline and having a short connecting partition 32 near its rear end. Within the partition 32 is formed a pair of openings 34. Within each of the openings 34 I mount a sleeve 36 of conducting material. On each side of the partition 32 and retained by the sleeve 36 is a washer 38.

An electric resistance wire 40 is wound around the exterior of the core 30 in grooves 42 formed in the core 30. One end of the resistance wire 40 is connected to one of the sleeves 36 in one of the openings 34. The other end of the same resistance wire 40 passes around a notch 44 formed in the outer edge of the core 30 and is connected to the other sleeve 36 on the inner side thereof.

It will be seen that the resistance wire has its ends connected to the sleeves 36 so that the resistance wire and core 30 form a complete heating unit or element adapted to be mounted upon the terminal posts 16 and 18. The sleeves 36 are of sufficient size to allow the terminal posts 16 and 18 to be inserted therein as clearly shown in Figures 2 and 3 of the drawings.

The posts 16 and 18 coming in contact with the sleeves 36 serve to transmit the electric current to the sleeves 36 and to the resistance wire 40. The entire assembly or heating unit A may be removed from the posts 16 and 18 when desired.

The partition 32 in the core 30 does not fill the entire end thereof but is cut-short so that a pair of ventilating openings 46 are formed wherein a circulation of air may be had longitudinally through the core 30.

One of the advantages of my structure resides in the heating unit which is adapted to be mounted on a pair of terminal posts and through such posts the heating unit is included in the electric circuit.

Some changes may be made in the construction and arrangement of the parts of my device without departing from the real spirit and purpose of my invention and it is my intention to cover by my claims, any modified forms of structure or use of mechanical equivalents, which may be reasonably included within their scope.

I claim as my invention:

- 20 1. In a device of the class described, a pair of spaced terminal posts insulated from each other, a heating unit comprising a tube-like core of non-conducting material having an end member, a pair of spaced openings 25 therein, sleeves of conducting material mounted in said openings said sleeves having flared ends for retaining them in the

openings in said end member and an electric resistance wire mounted on said core and having each end connected to one of said sleeves by extending under one of the flared ends thereof, said sleeves being adapted to receive said terminal posts whereby the heating unit is supported thereby and electrically connected thereto.

35 2. In a device of the class described, a reflector, a pair of spaced terminal posts insulated from each other, and supported on said reflector a heating unit comprising a tubular member of insulating material having an end disc a pair of openings therein for receiving said posts for supporting said member, an electric resistance wire surrounding said member, means within said openings of conducting material having the 40 ends of said wire connected thereto for contacting with said posts when said member is supported thereon and openings in said end disc to allow reflected heat to pass therethrough and thence through said tubular 45 member.

Des Moines, Iowa, February 6, 1928.

ERNEST S. JOHNSON.
